Primary Examiner — Karen E Kearney(74) *Attorney, Agent, or Firm* — NSIP Law**CLAIM**

The ornamental design for a display screen or portion thereof with a graphical user interface, as shown and described.

DESCRIPTION

FIG. 1 is a front view of a display screen or portion thereof with a graphical user interface showing our new design, the graphical user interface shown separately for ease of illustration; and,

FIG. 2 is another front view thereof, shown with environment. The broken line showings of the text, symbols, and image in FIGS. 1 and 2 and the mobile device in FIG. 2 are included for the purpose of illustrating portions of the article and form no part of the claimed design.

1 Claim, 2 Drawing SheetsFIG. 1

FIG. 2
